MULTIPLE SPEED PHONOGRAPH TURNTABLE DRIVES AND SELECTING MEANS THEREFOR

Herbert L. Hartman, Elyria, Ohio, assignor to The General Industries Company, Elyria, Ohio, a corporation of Ohio.

Application April 7, 1954, Serial No. 421,635

4 Claims. (Cl. 74—472)

My invention relates to multiple speed phonograph turntable drives and relates more particularly to improved selecting means for selecting the driving mechanism and maintaining the same in a desired position for driving the mechanism at a desired speed.

My present invention involves an improvement of apparatus disclosed in United States Letters Patent No. 2,438,266, granted to E. E. Ewing, and United States Letters Patent No. 2,538,265, granted to R. G. Metzner.

An object of my invention is to achieve change speed operation in a friction drive mechanism of the type referred to which will achieve the desired purpose in a simple, reliable, expeditious and effective manner.

Another object of my invention is to provide an improved mechanism for alternately moving a single idler wheel which is disposed intermediately of the phonograph turntable flange and the driving rotor whereby said idler wheel may be frictionally engaged with said flange and alternately with driver roller portions which are of different diameters.

A further object of my invention is to provide an improved mechanism for selecting a desired speed.

Another object of my invention is to provide an improved selector means for selecting the various speeds at which the phonograph mechanism is to be operated and in which the mechanism may be switched on and off with the same selector.

Other objects of my invention and the invention itself will be apparent to those skilled in the art to which my invention appertains by reference to the accompanying drawings, in which drawings:

Fig. 1 is a top plan view of an embodiment of my invention secured to a mounting plate exposed to view by assuming the cut-away of all other portions of a superposed turntable from a remaining mere fragment of record player portion, the latter being shown as engaged by the idler wheel of the said embodiment;

Fig. 2 is a section taken on the line 2—2 of Fig. 1;

Fig. 3 is a sectional view taken on the line 3—3 of Fig. 1;

Fig. 4 is a view taken on the line 4—4 of Fig. 1;

Fig. 5 is a view taken on the line 5—5 of Fig. 1;

Fig. 6 is a view taken on the line 6—6 of Fig. 1;

Fig. 7 is a view taken on the line 7—7 of Fig. 10 similar to Fig. 6 with the exception that the parts are shown in the position they assume when the operating lever of Fig. 1 is swung to an intermediate station indicated by the numeral 12;

Fig. 8 is a view similar to the view of Fig. 6 but showing the position that the parts assume when the operating lever of Fig. 1 is swung to the position indicated by the numeral 13;

Fig. 9 is a view taken on line 9—9 of Fig. 11 and is similar to the views of Figs. 6, 7 and 8 with the exception that the view is shown with the parts in the position which they assume when the operating lever of Fig. 1 is swung to the position indicated "off";

Fig. 10 is a top plan view of a portion of the mount-

2

ing plate of the lever and selector mechanism showing the parts in the position which they assume when the lever is being moved from its 33 r.p.m. position and moving toward its 45 r.p.m. position;

Fig. 11 is a top plan view similar to Fig. 10 but showing the parts in their "off" position.

Referring now to the drawings and referring more particularly to Figs. 1 and 2, the main supporting plate 51 is of sheet metal and the turntable 56 may be carried on a turntable post 55 and preferably the post 55 is journaled in a bearing tube 57 for rotation and mounted as shown in Figs. 1 and 2.

The turntable as shown is preferably provided with a pendant flange 58 having a cylindrical inner surface with which the rubber peripheral tread 60 of the idler wheel is fixedly engaged whereby rotation of the idler wheel may drive the turntable at a speed determined by rate of rotation of the said idler wheel.

The hub of the idler wheel 61 is provided with a bearing sleeve 62 drive fitted therein, said sleeve being journaled on an upright post 63 rigidly secured at its lower end to the yoke portion 64 of a U-shaped slide element, generally indicated at 70, said slide element having parallel arms 65 and 65' which make bearing fitting engagement within slideways afforded by notches laterally directed inwardly from the ends of the arms 66 and 66' of a mount element 67, in the manner disclosed in Letters Patent No. 2,421,910 issued to Herbert L. Hartman.

The oppositely extending pair of mount arms 66 and the oppositely extending parallel arms 66', are relatively interspaced in the longitudinal direction of the extent of the slide arms 65 and 65' and, with said slide arms disposed within the slots of said mount arms, the entire slide element 70, which by its yoke carries the idler wheel post 63 and idler wheel 61, may be moved longitudinally of the arms guided by the above designated slideways, subject to the restrictions imposed upon such movement by the tensile spring 68 and any engagement had by the periphery of the idler wheel 61 with the turntable flange 58 and also with the driving roller carried by the shaft 69 of the driving motor 71. The slide element 70 is further provided at its yoke end 64 with a projecting lug 41 projecting within the opening 42 disposed between the interspaced arms 65 and 65' and a spring 43 is seated upon said lug 41 and at its opposite end is seated within an opening 44 disposed within the block 67, and said spring 43 which preferably is weaker than spring 68 assists the action of the spring 68.

The stepped driving roller may, if desired, be formed separately from the shaft 69, but preferably said roller is afforded by providing the shaft with a reduced end 72 and a diameter increased portion 73, a diameter increased sleeve 74 of greater diameter than the relatively uppermost portions 72, 73, said sleeve portion 74 having a relatively larger end portion 75 which affords the portion of largest diameter of the steps 72, 73, 74 and 75 proceeding downwardly from the upper portion of the shaft 72 to the lowermost portion thereof. It is thus to be seen that four steps are provided on the driving shaft and it will be understood that these steps might be of greater number or of less number in various modifications of my invention.

The idler wheel mount or block 67 is further provided with a hub portion 94 having a cylindrical bore, and is journaled upon a relatively longer upstanding post 95 by a bearing fit, to permit such mount hub to be rotationally and longitudinally reciprocated on said post 95. The lower portion of the post 95 terminates in a reduced threaded end 95b which is extended through an aperture in the supporting plate 51 and openings in washers 95c, 95d, whereby the post is rigidly secured by the nut 95d to said plate 51. The idler wheel mount 67 is vertically

upwardly biased by means of a coil spring 96 loosely telescoped over the post 95 between said mount and the main supporting plate 51.

The reduced threaded end 95b of the post 95 is of such smaller diameter and of such length that it may loosely be projected through an aperture of a controlling lever 76, an intermediate portion of which is disposed between the washers 95' and 95" and beneath the plate 51.

The lever 76 terminates in a relatively longer arm 76' which terminates in an extending lug 76a which is adapted to contact the "off" and "on" switch indicated at "O" to turn the mechanism off and on. The controlling lever 76 is secured to the underside of the plate 51 by screw means 77 which are adapted to be projected through the longer arm 76' and through a selector lever to secure the same to said controlling lever by nut means 77.

The screw means, it is to be noted, project through generally C-shaped cutout portions in the main plate. It is to be noted further that the lever 76 is provided with a relatively short arm which terminates in an upstanding flange 79 which is so cut as to provide a notch 81 to afford three substantially parallel edge surfaces 84, 87 and 88, there being a pair of diagonal edge portions 85, 85' interconnecting the horizontal portions 87 and 88, and 88 and 84, said diagonal portions being disposed at preferably an angle of between 30° and 35° to the planes of the said horizontally extending edges.

The angle of inclination of the edges 85, 85', may of course be varied with corresponding variations in the required amount of throw of the handle portion H of the selector lever 100 which is connected by screw and nut means 77 to the controlling lever 76.

Disposed in cooperative position to the slot edges 87, 88 and 84 providing land surfaces for the camming surface 85, is a cam follower in the form of a preferably cylindrical stem 86 which is preferably secured to and affords a rearward extension of the idler wheel mount 67, said stem 86 affording a cam follower adapted to be cammingly moved to different lateral positions and to different levels as the result of lateral translatory movement of the camming lever flange 79.

Rotational movement of the mount 67 about the post 95 in the clockwise direction is opposed by the tension spring 68 which interconnects the free end of the slide 70 adjacent the idler wheel post 63 and a fixed portion of the main frame 51, shown at 68' in Fig. 1, said spring being so disposed as to constantly exert a pull upon the mount 67 tending to rotate it in the counter-clockwise direction.

In the apparatus of my invention the post 80, which is adapted to be engaged with a stem follower 86, operates as an abutment post ensuring that the adjustment operates particularly when shifting from a low speed driving arrangement to a high speed driving arrangement, accomplishes positiveness in the change speed operation, and ensures that the peripheral rubber tread of the idler wheel is not at any time subjected to an abrasive rubbing when passing over the upper corner of the lowermost largest driving roller step. At the same time, the provision of such an abutment post achieves a desirable result of accomplishing repeated uniform movements of the idler wheel whether or not the manually adjustable lever handle H is swung rapidly or slowly. The post 80 is further provided with a groove 80' to afford clearance for the stem 86 when the mechanism is in its "off position" which is disposed beyond the 78 r.p.m. position shown in the drawing.

The selector lever 100 of which the handle H is an integral part, said handle projecting outwardly from the main plate 51, as illustrated in the figures of drawing herein, is of generally arcuate form and is provided with a handle portion H, a stepped shoulder 101 connecting said handle portion to a portion of relatively wider extent, said portion being termed the intermediate portion 102, and a free end of relatively less width than the portion designated by the reference character 103.

The intermediate portion 102 is provided with apertures 102' through which the screw means 77 are projected, said screw means being also projected through aligned apertures in the controlling lever 76, the controlling lever 76 being disposed on the under side of the plate 51 and the selector lever 100 being disposed on the upper side of the plate 51, the screw means being disposed further through the severally arcuate spaced cut out portions shown at "c" and "d" in the main plate 51.

The free end 103 of the selector lever is provided with location notches, preferably four in number in the modification shown, namely, 106, 107, 108 and 109, being adapted to seat a detent button 112 mounted at the free end of a third lever 110 securely mounted on the main plate 51 at 111, said lever having an ear 113 disposed outwardly and intermediately of the rest of the lever, an aperture 114 in the ear 113 being adapted to seat a tension spring 115, which is secured at its other end to a down struck lug 116 of the plate 51. Said detent button is adapted to lock the speed change mechanism in any selected position by means of engagement of the button 112 with any of the notches 106-109, inclusive, the notch 109 being adapted to have engagement with the locking or detent button 112 when the speed selecting mechanism is in the position indicated for operation at 33 r.p.m., the notch 108 adapted to receive the button 112 to lock the mechanism in its 45 r.p.m. operating position, the notch 107 adapted to have the button seated therein when the handle is moved to the 78 r.p.m. position and the notch 106 is adapted to receive the said locking button when the mechanism is switched at its "off" position, at which time the lug 76a turns the off and on switch "off".

The lever 110 which carries the locating button 112 on the free end is adapted to move laterally in the end of the cut out "c" adjacent the lever connection 110 and an arrow indicates the direction of movement thereof. The spring 115 yieldingly exerts pressure when the portions of the selector lever disposed intermediate its adjacent notches are engaged by the button when the selector button is in movement from one speed change to another.

During the selection of speed by the operator, movement of the handle H causes the camming stem 86 to assume the positions shown in Figs. 6-9 inclusive. Fig. 6 shows the stem follower 86 in the 33 r.p.m. position. Fig. 7 shows the stem follower at an intermediate position between the 33 r.p.m. and the 45 r.p.m. position. Fig. 8 shows the stem follower 86 in the 78 r.p.m. position and Fig. 9 shows the stem follower in the "off" position and in the position permitted by the groove 80 to assist in clearance for the same in said position.

The operation of the change speed adjustment mechanism of my invention will now be described beginning with the parts shown in the position of Fig. 11 where the end 76a of the lever 76 is shown with the switch O in its "off" position. It will be noted that the idler wheel 60 in this position is in spaced relation with the stepped shaft 69 and the stem follower 86 is in the position shown in Fig. 9 with relation to the abutment post 80 and the upstanding flange 79 of the lever 76. Then when the handle H is grasped and the selector lever is moved in a counter-clockwise direction a slight distance the detent button 112 may be moved into engagement with the notch 107 at which time the stem follower 86, by reason of the movement of the flange 79 by means of movement of the lever 76 secured to the selector lever 100, is moved to the position shown in Fig. 8 and out of engagement with the abutment post 80, which moves the idler wheel 61 into peripheral driving engagement with the stepped roller 74 of the shaft 69 as indicated in solid lines in Fig. 5 and with said wheel constrained to such engagement by the retractive effort of the spring 68. The turntable is then rotated by means of the rotation of the idler wheel 61 engaged thereby at 78 r.p.m.

It will be noted that the end 76a of the lever 76 operates the switch O on its "on" position and the motor

being operated in any usual manner will rotate the idler wheel in a clockwise direction at the r.p.m., which is predetermined by the speed of the motor and the diameter of the roller step engaged and selected by the selector lever.

When the handle is moved to the next operative position, the stem follower 86 moves along the diagonal surface 85' withdrawing the idler wheel from engagement with the stepped roller 74 until the follower is seated against the edge surface 87, the locating button 112 is seated within the notch 108 to lock the same in its selected position and the rim 60 of the idler wheel 61 engages the reduced roller step 73 of the shaft 69 and the idler wheel is driven at a speed of 45 r.p.m.

When the handle is moved to the position shown in solid lines in Fig. 1, that portion of the lever 100 positioned intermediately of the notch 108 and 109 moves the detent button 112 out of engagement with the notch 108 and outwardly thereof and the idler wheel is moved upwardly from engagement with the step 73 of the shaft 69, as best illustrated in Fig. 10, and the stem follower 86 is disposed along the diagonal surface 85, as shown in Fig. 7, until it is positioned against the edge surface 84, as shown in Fig. 6, whereupon the locating or locking button 112 is seated within the notch 109, the idler wheel 61 has its rim portion disposed in engagement with the uppermost step of the shaft 69, namely, the step 72 as shown in Fig. 4 and the turntable is driven at 33 r.p.m. In each instance during change of speed when the handle is moved in a counter-clockwise direction, it will be noted, the idler wheel is progressively stepped up in engagement with the driving steps.

It will be clearly understood that the reverse movement of the handle, e.g. in the clockwise direction, will cause a reversal of the movement herein described except that in such reverse movement during said speed change the idler wheel is withdrawn from engagement with any of the steps during the speed change.

I claim:

1. A change speed mechanism for phonograph turntables of the type comprising a horizontally disposed idler wheel interposed between and peripherally engaged with a motor shaft driving roller and an annular flange of said turntable, a spring for resiliently maintaining said engagement, and a mount carrying said wheel near one end and being pivoted for swinging movement near the other end, said spring resiliently constraining the wheel carrying end of said mount toward one swinging direction, the combination with said wheel, spring, mount, roller and flange with said roller characterized by having relatively stepped axially aligned, friction driving roller portions of different diameters, a manually operable change speed controller comprising a handle alternately movable between limits in opposite directions, said speed controller having a plurality of laterally spaced peripheral notches, a pair of respectively cam and cam follower elements, one of said elements being movable in opposite directions responsive to corresponding movements of said handle and the other element adapted to be cammingly moved responsive to movement of the first element, said latter element adapted to communicate movement to said mount to displace said wheel from engagement from a predetermined roller step and to effect movement of said wheel to the plane of another roller step and said pair of cam and cam follower elements adapted to effect release of said wheel at said plane to permit said spring to retractively effect engagement of said wheel with said another roller step, locking means adapted to be seated within respective of said notches in said speed controller to lock said mechanism in the said selected speed, said speed controller carrying switch engaging means, a motor on and off switch adapted to be engaged by said switch engaging means upon movement of said handle.

2. A change speed mechanism for phonograph turntables of the type comprising a horizontally disposed idler

wheel interposed between and peripherally engaged with a motor shaft driving roller and an annular flange of said turntable, a spring for resiliently maintaining said engagement, and a mount carrying said wheel near one end and being pivoted for swinging movement near the other end, said spring resiliently constraining the wheel carrying end of said mount toward one swinging direction, the combination with said wheel, spring, mount, roller and flange with said roller characterized by having relatively stepped, axially aligned, friction driving roller portions of different diameters, a manually operable change speed controller comprising a handle alternately movable between limits in opposite directions, said speed controller having a plurality of laterally spaced peripheral notches, a pair of respectively cam and cam follower elements, one of said elements being movable in opposite directions responsive to corresponding movements of said handle and the other element adapted to be cammingly moved responsive to movement of the first element, said latter element adapted to communicate movement to said mount to displace said wheel from engagement from a predetermined roller step and to effect movement of said wheel to the plane of another roller step and said pair of cam and cam follower elements adapted to effect release of said wheel at said plane to permit said spring to retractively effect engagement of said wheel with said another roller step, locking means adapted to be seated within respective of said notches in said speed controller to lock said mechanism in the said selected speed, said speed controller carrying switch engaging means, a motor on and off switch adapted to be engaged by said switch engaging means upon movement of said handle, one of said notches adapted to be engaged by said locking means when the handle is moved to maintain said switch in said selected "on" or "off" position.

3. A speed selecting mechanism for phonograph turntables of the type comprising an idler wheel interposed between and peripherally engaged with a driving roller and an annular surface of said turntable, a mounting plate for said turntable, a mount secured to said plate above the same and carrying said idler wheel having a cam follower secured thereto, said speed selecting mechanism comprising a lever pivotally mounted below said plate, a selector portion disposed above said plate, said lever actuatable in response to movement of said selector portion, said selector portion comprising a handle, an intermediate portion, and a portion having a plurality of notches disposed along an outer edge thereof, said lever having a camming surface disposed upwardly therefrom, an arcuate guideway in said mounting plate, said camming surface projecting therethrough whereby it is disposed above said mounting plate, said lever being provided with an outwardly extending projection, a second lever secured to said mounting plate beneath said plate, locking means secured to said second lever and adapted to be seated by movement of said selector portion into different of said notches in response to manual movement of said selector portion, said movement of said selector portion causing the camming surface of said first mentioned lever to engage said cam follower to differently dispose said idler wheel with respect to said driving roller to drive the same at different speeds, "on" or "off" switch means adapted to be engaged by said projection of said first mentioned lever upon movement of said handle of said selector portion.

4. A speed selecting mechanism for phonograph turntables of the type comprising an idler wheel interposed between and peripherally engaged with a driving roller and an annular surface of said turntable, said driving roller characterized by having friction drive roller portions of different diameters, a mounting plate for said turntable, a mount secured to said plate carrying said

idler wheel having a first cam means associated therewith, said speed selecting mechanism comprising a lever having a selector portion secured thereto and disposed above said plate, said selector portion comprising a manually actuatable handle, and a portion thereof having a plurality of notches disposed along an outer edge thereof, said lever having a second cam means associated therewith, a camming surface disposed upwardly therefrom, an arcuate guideway in said mounting plate, said camming surface projecting therethrough whereby it is disposed above said mounting plate, said lever being provided with an outwardly extending projection, a second lever, locking means secured to said second lever and adapted to be seated by movement of said selector portion into different of said notches in response to 15 manual movement of said selector portion, said movement of said selector portion causing said second cam means to engage said first cam means to differently dis-

pose said idler wheel with respect to said driving roller to drive the same at different speeds, "on" or "off" switch means adapted to be engaged by said projection of said first mentioned lever upon movement of said selector portion, counter-clockwise movement of said selector portion progressively stepping up the idler wheel in engagement with different diameter driving steps of the driving roller and clockwise movement of said handle withdrawing the idler wheel during each speed change from engagement with any of the driving steps of the driving roller during speed change.
